United States Patent Office

Des. 188,750
Patented Sept. 6, 1960

188,750

COMBINED CLOSET BOWL AND TANK

Jack Henry Swann, 242 Forestwood Drive, Rosemere,
Quebec, Canada

Filed June 4, 1959, Ser. No. 56,209

Term of patent 14 years

(Cl. D4—5)

Fig. 1.

Fig. 2.

Fig. 3.

Fig. 1 is a perspective view of a combined closet bowl and tank embodying my new design;

Fig. 2 is a top plan view thereof;

Fig. 3 is a side elevational view thereof;

Fig. 4 is a front elevational view thereof; and

Fig. 5 is a rear elevational view thereof.

I claim:

The ornamental design for a combined closet bowl and tank, substantially as shown.
